UNITED STATES PATENT OFFICE.

CHARLES REMELIUS, OF NEW YORK, N. Y., ASSIGNOR TO THE COLUMBIA MACHINE WORKS & MALLEABLE IRON CO., OF BROOKLYN, NEW YORK, A CORPORATION OF NEW YORK.

ARMATURE-BANDING APPARATUS FOR LATHES.

No. 858,910.

Specification of Letters Patent.

Patented July 2, 1907.

Application filed March 22, 1907. Serial No. 363,862.

To all whom it may concern:

Be it known that I, CHARLES REMELIUS, a citizen of the United States, residing at the borough of Manhattan, city, county, and State of New York, have invented an Improvement in Armature-Banding Apparatus for Lathes, of which the following is a specification.

My present invention relates to a lathe attachment or apparatus for banding armatures or other similar devices and preferably comprises in combination with the frame and head and tail stocks of the lathe, a means for operating the axle of the head stock, a carriage movable longitudinally of the lathe, means attached to the carriage for carrying a reel, a series of tension devices also on said carriage, a swing guide arm pivotally mounted on the carriage and means against which the said swing guide arm is automatically moved in winding a band on an armature or other similar devices, as will be hereinafter more particularly described.

In the drawing, Figure 1 is an elevation of the lathe fitted with my improved banding apparatus, parts being shown as broken away. Fig. 2 is an end elevation of the same and Fig. 3 is a plan view of the carriage.

My improved banding attachment or apparatus is designed to be employed with a lathe which as is customary, comprises a frame consisting of end or upright support members *a b* and connecting members or rails *c d* secured to and extending between the end members *a b* in horizontal position and preferably parallel to one another so that their upper faces form tables and a slide-way upon which the carriage and the parts connected therewith may be adjustably positioned and as is also customary I provide at one end of the lathe the head stock *e* and at the other end the tail stock *f*. The tail stock *f* is adapted to be placed in any desired position as is customary in lathes, and the head stock *e* is provided with an axle *g* carrying a worm-wheel *h* preferably inclosed in a suitable casing and the axle *g* is driven from the drive shaft *k* by means of a worm *k* thereon meshing with the said gear. I also prefer to employ a friction clutch shown at *l* by means of which the drive shaft *k* is connected with an operating shaft *m* which may be driven from any suitable source of power. The member *n* of the friction clutch is slidably mounted on the axle *g* and is operated by means of a lever *l* pivotally mounted in a bracket *l*, the lower end of the lever *l* being pivotally connected to a link *14*, the opposite end of which is pivotally connected to an arm *15* secured to a rod *17* mounted in suitable bearings *18* and bases *19*. An arm *16* is also rigidly connected to the rod *17* and at its outer end carries a treadle *20*; and *21* is also an

arm connected to the rod *17* and may be a part of said rod or an extension of the arm *16*. This arm *21* is connected to a suitable base or plate *23* by means of a spring *22* from which construction it will be manifest that upon depressing the arm *16*, the rod *17* will be rocked against the action of the spring *22*; the arm *15*, link *14*, and the lower portion of the lever *l* being moved from left to right as shown in Fig. 2, and the upper portion of the lever *l* and the slideable member *n* of the friction clutch moved from right to left, thereby throwing in the clutch.

As shown in Fig. 1, in the use of my improved banding apparatus the armature *n* is mounted in the lathe between the head centers *10* and *11* of the axes of the head and tail stocks respectively, as is customary in all lathe work.

Now referring particularly to the part of the apparatus comprising my invention, I employ a carriage comprising a bottom plate or member *24*, side members *25 26* preferably arranged parallel to one another and at right angles to the bottom plate *24*. The side members *25 26* in similar positions are each provided with bearings *27* and in the bearings *27* I prefer to mount rollers *28*. Each roller *28* is provided with a flange *29* and the relation of the parts is such that when these rollers are mounted in their bearings they are adapted to lie upon the tried upper surfaces of the connecting members *c d*, with the flanges of the respective pairs of rollers engaging the outer edges of the said connecting members *c d*.

One side of the carriage is provided with a bracket *30* having an upright spindle or pin *31* adapted to receive a reel *32* and at the other side of the carriage a swing guide arm *33* is pivotally mounted at *34*. In the lower portion of this guide arm *33* adjacent to the point in which the same is pivoted I employ a roller *35* and in the upper or free end of the same a similar roller *36*.

The upper surfaces of the side members *25 26* are preferably curved in the arc of a circle and a spring member *37* is connected to the said swing guide arm *33* by means of a bracket *38*, and is so placed as to bear against the curved surface of the adjacent end member *25* to frictionally maintain the said swing guide arm in a given position, and adjacent to the bearings *27* in this side member *25* stop-faces *41* are provided which limit and determine the extent of the movement of the said swing guide arm *33*; and extending across the bottom member of the carriage, preferably in the upper surface thereof, I employ a series of tension rollers or other devices indicated at *39*.

Upon the use of the hereinbefore described apparatus and after the armature or other device to be bound

has been placed in the lathe, the carriage is manually or otherwise placed in the desired position on the connecting rails *c d*, and a wire 40 from the reel 32 is passed around the various tension rollers 39 over the rollers 35 5 and 36 and around the armature or other device to be bound, whereupon the lathe is started and in the turning of the same each successive convolution of the wire forming a band *o* will automatically shift the swing guide-arm 33 just sufficiently to maintain the convolutions of the wires forming the band in their juxtaposed positions.

I also prefer to employ a brake device comprising a flange 42 on the inner end of the movable member *l'* of the friction clutch, and a corresponding flange 43 on the frame of the head stock. The faces of these flanges 42 43 may be covered with roughened leather or other similar material; and as will be apparent, when the clutch is released the slideable member *l'* thereof will be returned by the action of the spring 22, and the face 20 of the flange 42 brought sharply into contact with the face of the flange 43, the friction between these parts stopping the lathe almost instantly.

I claim as my invention:

1. In a lathe, the combination with the end members, 25 connecting members, head and tail stocks, and means for actuating the axle of the head stock, of a movable carriage adapted to be adjusted on the said connecting members, a series of tension devices in the said carriage, a swing guide arm pivotally mounted on the said carriage, and means against which the said swing arm may be automatically moved in the banding operation.

2. In a lathe, the combination with the end members, connecting members, head and tail stocks, and means for actuating the axle of the head stock, of banding mechanism 35 comprising a movable carriage, means on the said carriage for supporting a reel, a series of tension devices on the said carriage, a swing guide arm pivotally mounted on the said carriage, and means against which the said swing arm

is automatically moved in the operation of the banding mechanism.

3. In a lathe, the combination with the end members, connecting members, head and tail stocks, and means for actuating the axle of the head stock, of banding mechanism comprising a movable carriage, means on the said carriage for supporting a reel, a series of tension devices on the said carriage, a swing guide arm pivotally mounted on the said carriage, means in the said swing arm for guiding the wire from the reel, and means for limiting the movement of the said swing arm.

4. In a lathe, the combination with end members, connecting members, head and tail stocks, the axle of the head stock and means for actuating the same, of banding mechanism comprising a carriage movable on the said connecting members and having a bottom member and side members connected thereto, means connected to said carriage for supporting a reel, a swing guide arm pivotally connected to said carriage, and means connected with the said guide arm for frictionally engaging one of the side members of said carriage.

5. In a lathe, the combination with end members, connecting members, head and tail stocks, the axle of the head stock and means for actuating the same, of a carriage having a bottom and side members at right angles thereto, means for supporting the carriage upon the said connecting members, means for supporting a reel at one end of the said carriage, a series of tension devices extending across said carriage, a swing guide arm pivotally mounted at the other end of said carriage, means in the swing arm for guiding the play of the banding wire as the same is taken from the reel, and means connected with the said swing guide arm and adapted to frictionally engage one of the said side members of the said carriage so that the said swing arm is moved automatically during the banding operation.

Signed by me this 7th day of March 1907.

CHARLES REMELIUS.
